Primary Examiner — Bridget L Eland*Assistant Examiner* — Lauren McVey(74) *Attorney, Agent, or Firm* — Brouse McDowell;
 Heather M. Barnes; Michael G. Craig(57) **CLAIM**

The ornamental design for a gas appliance ignition module, as shown and described.

DESCRIPTION

FIG. 1 is a front perspective view of a new design for a gas appliance ignition module;

FIG. 2 is a left elevation view of FIG. 1;

FIG. 3 is a top plan view of FIG. 1;

FIG. 4 is a front elevation view of FIG. 1;

FIG. 5 is a right elevation view of FIG. 1;

FIG. 6 is a rear elevation view of FIG. 1; and,

FIG. 7 is a rear perspective view of FIG. 1.

The broken lines are directed to environment; the broken lines form no part of the claimed design.

1 Claim, 7 Drawing Sheets(56)
